UNITED STATES PATENT OFFICE.

GEORGE F. HALL, OF NEWARK, ASSIGNOR TO CHARLES T. NIGHTENGALE,
OF PLAINFIELD, NEW JERSEY.

DESIGN FOR A BRAKE-SHOE FOR VELOCIPEDES.

SPECIFICATION forming part of Design No. 24,040, dated February 12, 1895.

Application filed November 6, 1894. Serial No. 528,095. Term of patent 3½ years.

To all whom it may concern:

Be it known that I, GEORGE F. HALL, a citizen of the United States, residing at Newark, in the county of Essex and State of New Jersey, have invented and produced a new and original Design for a Velocipede Brake-Shoe; and I do hereby declare the following to be a full, clear, and exact description of the invention, such as will enable others skilled in the art to which it appertains to make and use the same, reference being had to the accompanying drawing, and to the letters of reference marked thereon, which forms a part of this specification.

15 In the drawing, the figure represents in perspective a view of the brake shoe for velocipedes or the like, embodying the leading features of my new design.

The novel features of my new design for a 20 brake shoe are the marginal configuration of

the same, with a bent-up portion at one end having oblong openings therein, and the opposite end of the brake shoe being curved upwardly.

In the drawing, a designates the brake-shoe 25 having the flat surface thereof curved at one end, as at a' . At the opposite end the brake shoe is formed with a bent-up part a^2 in which are two oblong openings a^3 , as shown.

What I claim is—

The design for a brake shoe for velocipedes, or the like, herein shown and described.

In testimony that I claim the invention set forth above I have hereunto set my hand this 5th day of November, 1894.

GEORGE F. HALL.
